UNITED STATES PATENT OFFICE.

ERNEST J. SIMONSEN, OF CINCINNATI, OHIO.

ERASING APPARATUS.

Application filed April 7, 1927. Serial No. 181,809.

This invention relates to an erasing apparatus, and has for one of its objects to provide a novel, simple, durable and inexpensive apparatus of this character through the medium of which a part or the whole of a drawing may be erased easily and quickly and which shall embody an eraser holder and means by which the holder may be readily rotated at a rapid rate.

With the foregoing and other objects in view, the nature of which will become apparent as the description proceeds, the invention consists of the construction, combination and arrangement of parts hereinabove fully described and claimed, and illustrated in the accompanying drawing, wherein:

Figure 1 is an elevational view of the erasing apparatus,

Figure 2 is a top plan view of the erasing apparatus, and

Figure 3 is a sectional view taken on the plane indicated by the line 3—3 of Figure 2.

The erasing apparatus comprises an open frame 1 which is preferably of elongated rectangular formation and is provided in the end members or bars 2 and 3 thereof with lower bearings 4 and 5 and upper bearings 6 and 7. The bearings 4, 6 and 7 are in the form of sockets which open out through the inner sides of the bars 2 and 3, and the bearing 5 is in the form of an opening which extends through the inner and outer sides of the bar 3. A shaft 8 is journaled in the bearings 4 and 5, and a shaft 9 is journaled in the bearings 6 and 7. The bearing 4 and a collar 10, which latter is formed on the shaft 8 and contacts with the inner side of the bar 3, holds the shaft against endwise play in the frame 1, the shaft 9 being held against endwise play by its bearings 6 and 7. The shaft 8 is hollow and constitutes a holder for an eraser 11. The shaft 8 projects outwardly or forwardly beyond the bar 3, and the projecting end thereof is slotted to provide spring jaws 12 which normally stand away from or occupy an inactive position with respect to the eraser 11. A ring 13 which is mounted on the spring jaws 12 holds them in compressed or active position with respect to the eraser 11 so as to hold the eraser against casual endwise and rotative movements with respect to the shaft 8. The spring jaws 12 are provided with arcuated forward ends 12^a on which the compressing ring 13 is positioned and which hold the ring against

casual movement in an axial direction with respect to the clamping jaws 12. The rearward end of the shaft 8 is reduced as shown at 8^a, and fixed to said end thereof is a pinion 14. A gear 15 is fixed to the rear end of the shaft 9 and meshes with the pinion 14, and a knurled knob or wheel 16 is secured to the forward end of this shaft.

In practice the apparatus is used in connection with an erasing shield, and is supported in a manner to hold the forward end of the eraser 11 in contact with that portion of the drawing which is to be erased. The knob 16 is then turned with the result that the eraser 11 will be rotated at a rapid rate. All parts of the apparatus, with the exception of the eraser 11, are made of metal. The spring jaws 12 and the compressing ring 13 constitute a chuck which holds the eraser 11 in the holder 8. If desired the apparatus may be used for the purpose of supporting and operating any tool the action of which requires rapid rotation.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

1. A device of the character set forth, comprising an open frame, a hollow shaft rotatably mounted on the frame and provided with a chuck, a second shaft rotatably mounted on the frame in parallel relation to said first shaft, meshing gears fixed to the shafts, and an operating member secured to the second shaft and accessible through the open sides of the frame.

2. A device of the character set forth, comprising an open frame having its end members provided with alined bearing sockets and with an alined bearing socket and bearing opening, a shaft journaled in the alined bearing sockets, a hollow shaft journaled in the alined bearing socket and bearing opening and having an end thereof projecting beyond the frame member provided with the bearing opening, a chuck carried by said end of the hollow shaft, a collar carried by the hollow shaft and contacting with the inner side of the frame member provided with the bearing opening, meshing gears fixed to the shafts, and a knob carried by said first shaft and ac-

cessible through the open sides of the frame.

3. An erasing apparatus, comprising an open rectangular frame, a hollow shaft journaled in one side of said frame and adapted
5 to hold a bar of erasing material having one of its ends extending beyond an open end of said shaft, said open end of the shaft extending outside of said frame and provided with integral spring jaws having their free
10 ends deflected outwardly providing arcuate portions, a compression ring adjustably mounted on said jaws to hold them engaged with said bar of erasing material, the other

end of said shaft having a reduced extension, the frame provided with a socket journaling said extension, a second shaft arranged parallel with the hollow shaft and journaled within the frame, gearing connecting the two shafts, and a knurled wheel secured to the last mentioned shaft for manual operation of the shafts, said knurled wheel being larger in diameter than the width of the sides of the frame. 15 20

In testimony whereof I affix my signature.

ERNEST J. SIMONSEN.
